United States Patent Office

Des. 205,857
Patented Sept. 27, 1966

205,857

BROOCH OR SIMILAR ARTICLE

Lloyd F. Crisfield, 5418 Calle De Arboles,
Torrance, Calif.

Filed Oct. 24, 1965, Ser. No. 87,907

Term of patent 14 years

(Cl. D45—19)

FIG-1

The essential features of the design reside in the full line portions of the drawing.

I claim:

The ornamental design for a brooch or similar article, substantially as shown and described.
